Primary Examiner — Deanna L Pratt*Assistant Examiner* — Lilyana Bekic(74) *Attorney, Agent, or Firm* — John R. Thompson; Stoel Rives LLP**CLAIM**

We claim the ornamental design for a slim case, as shown and described.

DESCRIPTION

FIG. 1 is a perspective view of a back side of a slim case for a portable electronic device.

FIG. 2 is another perspective view of the back side of the slim case.

FIG. 3 is a side view of a side edge of the slim case.

FIG. 4 is a view of one end of the slim case.

FIG. 5 is a view of an opposing end of the slim case.

FIG. 6 is a perspective view of a front side of the slim case.

FIG. 7 is a plan view of the front side of the slim case; and,

FIG. 8 is a plan view of the back side of the slim case.
